UNITED STATES PATENT OFFICE.

CLARENCE P. BYRNES, OF SEWICKLEY, PENNSYLVANIA.

MOTOR-COOLING SYSTEM FOR SELF-PROPELLED VEHICLES.

Application filed January 3, 1918. Serial No. 210,205.

To all whom it may concern:

Be it known that I, CLARENCE P. BYRNES, a citizen of the United States of America, residing at Sewickley, in the county of Allegheny and State of Pennsylvania, have invented a new and useful Improvement in Motor-Cooling Systems for Self-Propelled Vehicles, of which the following is a full, clear, and exact description, reference being had to the accompanying drawings, forming part of this specification, in which—

Figure 1 is a diagrammatic plan view partly broken away showing one form of the invention;

Figure 2 is a similar view showing another form of the invention; and

Figure 3 is a similar view showing a further modified form applied to V-shaped engines.

The invention relates to the drawing of air through the radiator of a self-propelled vehicle, having a water-cooled engine connected with the radiator.

Heretofore, a motor-driven fan has been used to draw air through the radiator to a sufficient amount to keep the engine cooled to the desired degree. This fan, particularly at certain speeds, consumed a considerable amount of power developed by the motor.

The present invention aims to do away with the fan and provides an air injector system which is applied to the vehicle in such a manner as to not interfere with the usual parts thereof, and utilizes the exhaust gases from the motor to draw air through the radiator.

In the preferred forms, an air chamber or chambers is provided back of the radiator and around the motor and from which air injectors lead at the sides of the fly wheel for the drive shaft, the motive fluid for the air injectors being supplied from the exhaust having pipes forming part of the air injector system.

In the drawings, referring to Figure 1, 2 represents the motor and 3 the radiator of an automobile of ordinary type. 4 is the fly wheel and 5 a portion of the drive shaft. The motor 2 is set in the air chamber 6, which is preferably substantially air-tight. It may be closed at the rear by the partition 7 and at the top and sides by the usual hood structure 8, which in this form is preferably imperforate, not having the usual louvres or air outlet apertures. The bottom of the chamber may be formed by the usual pan or

crank case, and the front is, of course, formed by the radiator itself.

In the partition 7 at the sides of the fly wheels are arranged air injectors 9, into which lead the jet pipes 10, connected with the exhaust pipes of the motor cylinders. The injectors may lead back to a muffler or mufflers.

When the motor is in operation, air will be sucked back through the radiator and through the closed engine chamber and thence back through the injector pipes to the mufflers. The weight of air drawn through will, of course, depend on the speed of the motor and the volume of exhaust gases.

In Figure 2, I show a form similar to that of Figure 1, except that the motor is cased in so that the engine chamber in the rear of the radiator 3^a need not be air-tight. In this case, longitudinal partitions 11 lead rearwardly from the radiator on each side of the motor, these joining at the front at the center of the radiator so as to divide the air into two currents, each of which passes back to its air injector 9^a. The channels 12 formed partly by the partitions will, of course be air-tight, and the engine may be reached through movable closures in these partitions, or by hinging the channels at the front so that each can be swung back. In this case, the exhaust pipes are shown as merging into a single exhaust pipe at each side marked 10^a. The air injectors may also be placed farther forward, one at each side of the engine, the exhaust pipes, in this case, being led from the front of the engine structure; so that the combined air and waste gases pass back at each side of the engine and past the fly wheel. In this case the air chambers at the rear of the radiator may be simply large enough to properly divide the radiator and contain the exhaust injectors.

In Figure 3, I show a form similar to Figure 1, except that the engine is a V-shaped engine there being an exhaust pipe 10^b from each set of cylinders leading back to the injector 9^b. The exhaust pipes are shown as located in the trough between the sets of engine cylinders, though they may be outside, if desired.

The exhaust pipes may also lead outwardly through the hood, if desired. In this case, as in Figure 1, the air compartment containing the motor should be substantially air-tight, so that all air sucked in

by the injectors must pass through the radiator and thus cool the water, which, in turn, serves to cool the motors.

The advantages of my invention will be obvious to those skilled in the art, since the usual suction fan is discarded, with the consequent advantages of greater simplicity and also less loss of power.

The water-cooled motor may be of any desired type as may also the radiator; the air chamber between the radiator and the injectors may be varied, and many other changes may be made, without departing from my invention.

15 I claim:

1. In a cooling system for motor vehicles, a multi-cylinder internal-combustion water-cooled motor, a radiator connected to the water-cooling system for the motor, an air chamber arranged at one side of the radiator to receive the air passing therethrough, said air chamber having a plurality of Venturi formed air outlets, the exhaust channels for the engine being combined into a plurality of exhaust outlets less than the number of motor cylinders, each air Venturi outlet having an exhaust outlet substantially concentric therewith, substantially as described.

2. In a cooling system for motor vehicles, a water-cooled motor at the front of the chassis, a radiator in front of the motor and connected with the water-cooling system, an air chamber at the rear of the radiator, and

a motor exhaust injector system having a plurality of injectors leading rearwardly at 35 opposite sides of the motor, substantially as described.

3. In a cooling system for motor vehicles, a water-cooled motor at the front of the chassis, a radiator connected to the water-cooling system for the motor and located in front of the motor, an air chamber at the rear of the radiator and at least partially enclosing the motor, and a motor exhaust injector system arranged to draw air through 45 the radiator, said injector system having injectors leading from the side portions of the air chamber, substantially as described.

4. In a motor-propelled vehicle, a radiator in front of the chassis, an air chamber system at the rear of the radiator and at least partially enclosing the motor, injector pipes leading from the air chamber at opposite sides of the fly wheel, and exhaust pipes leading from the motor to the air injectors, 55 substantially as described.

5. In a cooling system for motor vehicles, a water-cooled motor at the front of the chassis, a radiator in front of the motor, and a plurality of air injectors located in the rear 60 of the radiator at opposite sides of the engine each connected with the engine exhaust; substantially as described.

In testimony whereof, I have hereunto set my hand.

CLARENCE P. BYRNES.
